UNITED STATES PATENT OFFICE.

CHARLES FRIZELL, OF BOSTON, MASSACHUSETTS.

IMPROVEMENT IN STEP-LADDERS.

Specification forming part of Letters Patent No. **140,578**, dated July 8, 1873; application filed May 29, 1873.

To all whom it may concern:

Be it known that I, CHARLES FRIZELL, of Boston, in the county of Suffolk and State of Massachusetts, have invented a new and useful Improvement upon the Step - Ladder described in the application filed in the Patent Office by myself on the 10th day of April, A. D. 1873, for the obtaining of Letters Patent therefor.

And this invention consists in combining diagonal rods with the side string pieces, and tie-rods which unite the same, by which the sides are greatly strengthened, without materially increasing their weight.

The accompanying drawing represents a side elevation of the ladder with this improvement applied.

In the drawing, *a a* are the string-pieces,

and *b b* are the tie-rods, the end of which are, respectively, secured in bars *a*. *c c* are short pieces which serve to unite the respective extremities of bars *a*, and form a broader bearing. *d d* are diagonal braces or rods, which are secured in bars *a*, as shown, and which serve as stays, by which the compressive strain upon the upper and the tensile strain upon the lower bar are economized for their reciprocal support.

What I claim as my invention is—

The diagonal rods *d*, in combination with bars *a a* and tie-rods *b*, substantially as and for the purposes specified.

CHARLES FRIZELL.
